INTERNAL ELECTRIC STARTING-VAPORIZER FOR COMBUSTION-ENGINES.

No. 909,898.

Specification of Letters Patent.

Patented Jan. 19, 1909.

Application filed April 16, 1907. Serial No. 368,536.

To all whom it may concern:

Be it known that we, HARRY HERTZBERG, residing at New York, borough of Brooklyn, and State of New York, ABBOT AUGUSTUS 5 Low, residing at Horseshoe, and State of New York, and AUGUST WASSMANN, residing at Astoria, Long Island, and State of New York, citizens of the United States, have invented a certain new and useful Internal 10 Electric Starting-Vaporizer for Combustion-Engines, of which the following is a specification;

This invention is an internal vaporizer particularly adapted for use in or adjacent to 15 the cylinder of a hydrocarbon combustion engine.

More particularly, the type of engine to which the invention relates is operated by the combustion of kerosene which is first mixed 20 with air to produce an explosive vapor, the resulting gaseous mixture being drawn into the cylinder by the suction of a piston.

In starting an engine of this class the oil present in the explosive vapor, when admitted to the cylinder, has a tendency to 25 condense by being brought into contact with the cold surface of a cylinder and the head thereof.

This invention overcomes said objections in 30 a simple, efficient, expeditious and economical manner, and one of its objects is secured by electrically heating a metallic vaporizing surface with which the explosive mixture is brought into contact. Said vaporizing surface 35 is heated electrically to the required temperature in a very brief time for the purpose of vaporizing the fuel when starting the engine. In a few minutes of time it is found that the engine becomes sufficiently heated up, 40 by the combustion of the explosive charges, to vaporize the successive charges of fuel, and to continue in operation so long as such charges are supplied to the cylinder and are exploded by the igniter; and under such conditions, the preliminary electric starting vaporizer is discontinued from service and, the engine thereafter is operated by the combustion 45 of charges which are vaporized by a permanent internal vaporizer.

50 In the operation of engines equipped with permanent internal vaporizers and employing kerosene as the fuel, it is found that there is a liability of premature combustion

of the charges of explosive mixture by such internal vaporizers; but in this invention we 55 employ a form of internal vaporizer which eliminates all possibility of such premature explosions, and which operates efficiently in converting the mixture of oil and air into a vapor adapted to be exploded by a suitable 60 igniter or spark plug. Furthermore, certain forms of the electrically-heated starting vaporizer of this invention are each constructed in such manner that the explosive mixture will circulate through and around said vaporizer after the engine is started, such charges of the mixture being thereafter vaporized, whereby the circulation of air and fuel tends to overcome excessive heating and consequent deterioration of said starting vaporizer.

In the accompanying drawings, we have illustrated different practical embodiments of the invention, but the constructions shown therein are to be understood as illustrative 75 only, and not as defining the limits of the invention.

Figure 1 is a vertical sectional elevation illustrating one form of the present invention in connection with an ordinary type of 80 combustion engine. Fig. 2 is a plan view of an electrically heated starting vaporizer adapted to be used in connection with the engine of Fig. 1. Fig. 3 is a plan view of another form of electrically heated starting 85 vaporizer. Fig. 4 is a vertical section on the line 4—4 of Fig. 3. Fig. 5 is a plan view of still another form of starting vaporizer. Fig. 6 is a cross section on the line 6—6 of Fig. 5. Fig. 7 is a vertical section, partly 90 an elevation, showing a form of starting vaporizer adapted to establish an eddy current with in the permanent vaporizer of a combustion engine.

A designates a portion of an engine cylinder, and B is the head thereof. As usual the cylinder is provided with a water jacket, a, and the head, B, is chambered at b to provide with the circulation of a cooling medium, such as water, through said cylinder 100 and its head.

C designates a casing herein shown as being attached to the head, B, said casing forming a mixing chamber c, in which air and a suitable combustible liquid are mixed 105 mechanically in order to produce an explo-

sive charge which is vaporized and thereafter admitted to the engine cylinder so as to be exploded therein by an igniter or spark plug, indicated at D in Fig. 1. As shown, 5 the casing, C, is provided with an air inlet, e, the area of which is controlled by a suitable valve, E. Into the chamber, c, is supplied a combustible fuel, such as kerosene, by means of a jet nozzle, F, with which 10 communicates a suitable liquid pipe, f. Between the air valve, E, and the jet nozzle, F, is a diaphragm, G, which is formed, preferably, by a metallic gauze. The jet of liquid supplied by the nozzle, F, strikes against the 15 diaphragm, G, and is broken up into a fine spray thereby. The air admitted by the valve, E, is drawn through the diaphragm when the engine piston is on its back stroke and the valve, H, is opened, the air and the 20 mechanically divided liquid being mixed in the chamber c, before they are converted into a fixed vapor by the action of the vaporizer. A bushing, I, is fitted in a central opening of the cylinder head, B, said bushing being 25 flanged in order to receive suitable bolts by which it is fastened to the cylinder head. The lower part of the bushing is provided with a valve seat adapted to be engaged by the inlet valve, H, the latter having a stem, h, 30 on which acts a suitable spring, h', adapted to keep the valve normally closed on its seat. The parts heretofore described may be of the usual or any preferred construction, and the valve, H, may be operated positively by 35 connections with a moving part of the engine, and in Fig. 1 the stem, h, of said valve is connected with a lever, H', which is operated by a rod, H'', from a cam or other moving part of the engine.

40 The bushing, I, is provided with an inlet passage i, by which the mixture of air and fuel is admitted to the vaporizer which is, in this invention, located within the upper part of the engine cylinder, A.

45 It is preferred to equip the engine with two vaporizers, both located internally of the piston chamber, one of said vaporizers being electrically heated for the purpose of quickly producing a hot surface at the time 50 of starting the engine so as to vaporize the first charges of explosive mixture admitted to the piston chamber, and the other vaporizer being heated by the combustion of said charges and operating on the discontinuance 55 of the starting vaporizer so as to remain in operation during the continued service of the engine.

The permanent vaporizer is shown in Fig. 1 as consisting of a bowl shaped vessel, J, 60 arranged in the upper portion of the piston chamber, a', of the cylinder, A. This bowl shaped vessel is attached in any suitable way to the cylinder or to the head thereof, but as shown, the cylinder head, B, is provided 65 with a flange, b', having an internal thread

into which is screwed the male threaded upper edge portion of the vaporizer, J. Said vaporizer is thus suspended or supported directly below the inlet valve, H, and communication between the valve and the piston chamber, a', is established by an opening, j, in the vaporizer. The diameter of the opening, j, is less than the area of the intake valve, H, and said opening is directly below said intake valve, whereby a combustible 75 mixture (of air and oil) admitted by the intake valve is caused to circulate within a chamber of said vaporizer, J. This circulation insures a more complete admixture of the combustible vapor. The diameter of the 80 opening, j, may differ in the vaporizers used in the different engines, according as actual conditions of service may require.

The starting vaporizer is heated electrically at will, and after the engine is in 85 service the electric current is cut off from the starting vaporizer, in order that it may be thrown out of service and the engine may run by vaporizing the fuel in contact with the surfaces of the vaporizer, J. Said starting vaporizer is shown in Fig. 1 as being within the chamber of the permanent vaporizer, J, between the intake valve, H, and the bottom portion of said vaporizer, J.

Various forms of starting vaporizers are 95 shown in Figs. 1 to 7 inclusive, of the drawings, and it is desired to state that we prefer to construct each starting vaporizer with slots, openings or the like, for the purpose of permitting the air and oil to circulate 100 through said starting vaporizer when the engine is operating after normal conditions, such circulation of oil and fuel tending to overcome undue heating of said starting vaporizer and consequent deterioration thereof. It is not intended, however, to limit the invention to a perforated vaporizer for the reason that it may be imperforate as shown in Figs. 3 and 4, in which case the air and oil will circulate externally to and around said 110 starting vaporizer.

In the construction shown in Figs. 1 and 2, the starting vaporizer, K, is of an 115 annular form and constructed to resemble a grid, whereby the desired circulation openings or slots are produced therein. Said vaporizer, K, is composed of a mass of metal adapted to be quickly heated by an electric current and presenting a surface against which may impinge the combustible mixture admitted by the intake valve. As shown, the vaporizer, K, of Figs. 1 and 2 is composed of a hollow rim, k, and a plurality of cross bars, k', the latter being arranged to provide the slots or openings, k'', through 125 said vaporizer. The hollow rim, k, accommodates an electrical resistance which is insulated from contact with the mass of metal. Any suitable means for electrically heating the mass of metal composing the vaporizer, 130

K, may be employed, such for example as electric heaters of the type disclosed in a prior application filed by Hertzberg and Low as joint inventors, but for the purposes of 5 this application it is considered sufficient to illustrate the electric resistance at l in Fig. 1 and to inclose said resistance within a layer or layers of insulating material, l' . The electrical resistance may consist of a 10 metallic wire or ribbon wound non-inductively on a core, preferably of mica, said resistance and the core being inclosed between other layers of mica forming the insulations, l' . The current is adapted to 15 be conducted to the electrical resistance by wires, m , which are led through an insulating bushing or sleeve, m' , shown in Fig. 1 as extending through the head, B, of the cylinder. The electrically heated vaporizer, 20 K, is adapted to be secured to and supported within the vaporizer, J, by suitable means, but as shown in Figs. 1 and 2 said starting vaporizer, K, is attached to lugs, j' , of the vaporizer, J.

25 When starting the engine the cylinder and the vaporizers are in a cold condition, and in order to avoid the use of naphtha, benzine or other highly volatile fluid we admit an electric current to the resistance 30 of the starting vaporizer, K. The current is switched on for a few minutes in order that the resistance, l , may quickly heat up a mass of metal composing the vaporizer, K. The air valve, E, having been opened, 35 the fuel pump is started in order to inject a quantity of kerosene oil into the chamber, c , and when the engine piston is moved downwardly, the valve, H, is opened and a charge of combustible mixture is thus 40 admitted into the engine. As the mixture passes the intake valve, H, it strikes the hot surface of the vaporizer, K, whereby the mixture is converted into vapor and circulates in the chamber of the vaporizer, J, 45 finding an exit therefrom through the opening, j , into the piston chamber, such combustible vapor being compressed in the piston chamber and exploded by the igniter, D. It is only necessary to admit a few 50 charges of combustible vapor to the engine cylinder, which charges are vaporized by the vaporizer, K, and to explode said charges in the cylinder, before the vaporizer, J, becomes sufficiently heated to convert the 55 successive charges of combustible mixture into vapor, and when such conditions obtain the electric current is cut off from the vaporizer, K, and the charges of combustible mixture are converted into vapor by contact 60 with the hot surfaces of the vaporizer, J. The passage of air and fuel through the openings of the vaporizer, K, minimizes the tendency of the vaporizer to burn out under the heat developed by the engine. 65 Furthermore, the vaporizer, J, is secured

mechanically to and in contact with the chambered water cooled head, B, of the cylinder, and this construction overcomes any tendency of the vaporizer, J, to become so highly heated as will produce premature 70 ignition of the combustible vapor.

In Figs. 3 and 4 we have shown an imperforate construction of the starting vaporizer, K'. It is composed of a body or mass of metal presenting continuous top 75 and bottom surfaces, and said body is shown as being circular, although the shape and size of the vaporizer is not important. Said vaporizer is provided with a chamber, k^2 , adapted to contain the insulating layers of 80 material, l' , which confine the resistance layer, l , substantially in contact with the body or mass of metal, whereby the heat developed by the inclosed resistance is transmitted directly to and absorbed by the mass 85 of metal composing the vaporizer. The conductors, m , are connected electrically with the resistance, l , and the entire vaporizer is adapted to be supported within the chamber of the hollow vaporizer, J, in substantially 90 the manner hereinbefore indicated. Said vaporizer, K', is adapted to lie directly below and opposite to the intake valve, and the combustible mixture admitted by said valve strikes said vaporizer so as to be converted into vapor which circulates around the edge of the body, K', and thence passes through the opening, j , of the vaporizer, J. 95

Another construction of the grid like starting vaporizer is shown in Figs. 5 and 6 100 of the drawings, wherein the vaporizer, K², is constructed with the circulation slots or openings, k^2 , for the passage therethrough of the combustible mixture. Said vaporizer, K², somewhat resembles the grate used in 105 stoves, although this particular form is not a material part of the invention. The vaporizer consists of a hollow rim, k , an interior rim, k^4 , concentric with said hollow rim, k , and radial webs or bars k^5 , which 110 join the members, k , k^4 . The members, k , k^4 , contain the electrical resistances, l , l^2 , each of which is electrically insulated from the walls of the hollow parts, k , k^4 ; and said resistances are connected in multiple 115 circuit by the wires m , m^2 . It is evident that the vaporizer, K², of Figs. 5 and 6 may be supported within the hollow vaporizer, J, so as to lie below the intake valve, H, and the electric current is adapted to be supplied 120 to the resistances, l , l^2 , for the purpose of quickly heating the body or mass of metal of said vaporizer, K². Said vaporizer is employed in starting the engine to convert 125 into vapor the combustible mixture of air and kerosene, and thereafter the current is cut off from said vaporizer so that the mixture will flow through the opening, k^2 , and strike the hot surface of the vaporizer, J.

In Fig. 7 of the drawing, we have shown 130

a construction wherein the electrically heated starting vaporizer is adapted to set up or establish an eddy current of the combustible mixture for the purpose of more thoroughly commingling the oil and kerosene, one with the other, prior to or at the time of the conversion of the said mixture into vapor. This establishment of the eddy current is adapted to be secured, in a measure, by 10 the construction of the starting vaporizer shown in Fig. 1, but it is clear that the construction of Fig. 7 secures this end to somewhat better advantage. The vaporizer, M, is constructed or fashioned to present a 15 curved surface to the inflowing charge of combustible mixture, and when said charge impinges on said curved surface it is caused to rebound therefrom in a substantially spiral manner for the purpose of securing 20 the eddy current. As shown, the vaporizer, M, consists of a mass of metal which is chambered to receive the electrical resistance and the necessary insulations therefor. Said vaporizer is preferably in the form of a 25 ring having inner and outer walls, which in cross section are curved as at o, o'. The vaporizer, M, is supported by any suitable means within the vaporizer, J, below the intake valve, H, and the inner curved wall, 30 o, of said vaporizer is directly in the path of the combustible mixture adapted to be drawn into the cylinder when the valve, H, is opened, whereby the charge strikes the surface, o, and rebounds therefrom to set 35 up the eddy current. The circulation and eddying of the vapor secures a more thorough admixture of its ingredients, and said vapor is adapted to be drawn into the piston chamber by the suction created by 40 the movement of the piston therein.

The principal advantage secured by this invention is that we are able to start and operate the engine by one kind of fuel, preferably kerosene. When starting an ordinary combustion engine adapted to use this fuel, or one similar to it, the oil present in the explosive mixture condenses by contact with the cold surfaces of the cylinder and its head. To overcome such objection, it 45 has been customary to use one kind of fuel, such as naphtha, in starting the engine, and when the parts are heated, the other fuel, kerosene, is supplied for the continued operation of the engine. This expedient, however, is not desirable for the reason that it 50 is necessary to always keep on hand two available supplies of fuel, in consequence of which two tanks and other parts must be provided. We are able by this invention to 55 quickly heat one vaporizer by the action of an electric current for the purpose of starting the engine with kerosene, and when the other vaporizer is sufficiently heated by the combustion of the charges, the electrically- 60 heated vaporizer is cut out of service, and 65

the engine is operated by the vaporization and combustion of other charges of the same kind of fuel.

Having thus fully described the invention, what we claim as new, and desire to 70 secure by Letters Patent is:—

1. In an engine of the class described, a hollow vaporizer located internally of the engine-cylinder, and a starting vaporizer within the aforesaid hollow vaporizer. 75

2. In an engine of the class described, a hollow vaporizer located internally of the engine-cylinder, a starting vaporizer within the aforesaid hollow vaporizer, and means for electrically heating said starting vaporizer. 80

3. In an engine of the class described, an engine-cylinder, an intake valve by which a combustible mixture is admitted to said cylinder, an internal thermostatic vaporizer, 85 and a starting electrically-heated vaporizer between the intake valve and the thermostatic vaporizer.

4. In an engine of the class described, an engine cylinder, a chambered vaporizer 90 within said cylinder, and an electrically-heated vaporizer within the chamber of the first named vaporizer.

5. In an engine of the class described, an engine-cylinder, a chambered vaporizer 95 therein, a starting vaporizer partially surrounded by said chambered vaporizer, and means for electrically-heating said starting vaporizer at will.

6. In an engine of the class described, a 100 combustion chamber, a hollow vaporizer therein, a slotted starting vaporizer incased by said hollow vaporizer, and means for electrically-heating said starting vaporizer.

7. In an engine of the class described, an 105 engine cylinder, an intake valve, a hollow vaporizer over the inlet afforded by said valve to the cylinder, a starting vaporizer incased by the first named vaporizer, said starting vaporizer having openings for the 110 circulation of a combustible vapor therethrough, and means for electrically-heating said starting vaporizer.

8. In an engine of the class described, an engine cylinder, an intake valve thereto, a 115 hollow vaporizer across the inlet afforded by said valve to the cylinder, a starting vaporizer having openings for the circulation of a combustible vapor and comprising a mass of metal which forms a vaporizing surface, 120 said starting vaporized being incased by the first named vaporizer, and means for electrically-heating said mass of metal of the starting vaporizer.

9. In an engine of the class described, an 125 engine cylinder, an intake valve, a vaporizer within said cylinder and across the path of combustible mixture admitted thereto by said valve, another vaporizer within the first named vaporizer and lying in the path of a 130

combustible mixture admitted by said valve, and means for electrically heating the second named vaporizer at will.

10. In an engine of the class described, an engine cylinder, an intake valve, a hollow vaporizer within said cylinder, and an electrically-heated starting vaporizer within a chamber of said hollow vaporizer, said starting vaporizer presenting a curved surface 10 in the path of a combustible mixture admitted by the valve, whereby the starting vaporizer is adapted to set up an eddy current in the combustible mixture simultaneously with the conversion of said mixture into a combustible vapor.

11. In an engine of the class described, an engine cylinder, an intake valve, a hollow vaporizer within said cylinder, and an electrically-heated starting vaporizer within a chamber of said hollow vaporizer, said starting vaporizer presenting a concave surface in the path of a combustible mixture admitted by said intake valve.

12. In an engine of the class described, a cylinder, an intake valve, a chambered vaporizer, and an electrically-heated vaporizer between the valve and the first named vaporizer, said second named vaporizer being provided with openings through which air and fuel are adapted to pass under normal conditions in the operation of the engine, whereby the second vaporizer is kept from undue heating and the mixture is adapted to be vaporized by contact with the first vaporizer.

13. In an engine of the class described, a cylinder, an intake valve, a chambered vaporizer within said cylinder, and an electrically-heated starting vaporizer incased by said chambered vaporizer, said starting vaporizer being spaced relatively to the walls

of the chambered vaporizer for the circulation of a combustible mixture between the aforesaid vaporizers.

14. In an engine of the class described, a cylinder, an intake valve, a vaporizer in the cylinder opposite to the valve, said vaporizer being closed except for an opening in line with the valve, whereby a mixture admitted by the valve is caused to circulate within the vaporizer and to be drawn through the opening thereof, and an electrically-heated starting vaporizer located between the valve and the opening in the aforesaid vaporizer.

15. In an engine of the class described, two vaporizers located within an engine cylinder, one of said vaporizers being heated by the combustion of charges admitted to the engine cylinder, the other vaporizer being incased by the aforesaid vaporizer and provided with means for electrically heating the same.

16. In an engine, two vaporizers located within a cylinder of said engine, one of said vaporizers substantially incasing the other vaporizer, and electrical means for initially heating the incased vaporizer, the other or incasing vaporizer being adapted to be heated subsequently by the combustion of charges which are admitted to the cylinder.

In testimony whereof we have signed our names to this specification in the presence of two subscribing witnesses.
